CALCULATING MACHINE

Carl M. Friden, Oakland, Calif., assignor to Friden
Calculating Machine Co., Inc., a corporation of
California

Application July 4, 1939, Serial No. 282,768

8 Claims. (Cl. 235—137)

My invention relates to calculating machines and is concerned more particularly with the provision of improved tens transfer mechanism to provide for increased transfer capacity in a calculating machine.

It is the general object of the invention to provide an improved tens transfer mechanism for a calculating machine.

Another general object of the invention is to provide an improved calculating machine combining tens transfer mechanism of the cyclic type with non-cyclic transfer mechanism to increase the transfer capacity of a machine.

Another object of the invention is to provide improved tens transfer mechanism which can be readily installed to provide extra transferring orders in a calculating machine.

Another object of the invention is to provide an improved tens transfer mechanism of the reversible type which is controlled by the usual reversing means of the calculating machine.

Other objects and advantages of the invention will be apparent from the following description thereof which is made with reference to the accompanying drawings, in which:

Fig. 1 is a fragmentary longitudinal section through the rear portion of a calculating machine embodying my invention with a part of the actuating means broken away to illustrate the construction more clearly.

Fig. 2 is a fragmentary plan view of the rear portion of the machine with the carriage and other parts removed.

Fig. 3 is a transverse sectional elevation taken as indicated by the line 3—3 in Fig. 2.

Fig. 4 is a longitudinal sectional elevation of a portion of the machine, the view being taken in a plane indicated by the line 4—4 of Fig. 2.

Fig. 5 is a fragmentary bottom plan view of one end of the carriage taken as indicated by the line 5—5 in Fig. 1.

Fig. 6 is a fragmentary plan view with certain portions omitted and showing one unit or one order of the non-cyclic transfer mechanism as conditioned for operation by movement of the plus-minus registration control means.

Fig. 7 is a view similar to Fig. 6, but showing the transfer unit as operated after a transfer is determined from the next lower order of the machine.

The present invention is shown as embodied in a calculating machine of the Thomas type, as shown for example in my co-pending application Serial No. 724,482, filed May 8, 1934. Generally a machine of this type includes a body in

which the selecting, actuating and transfer actuating mechanisms are mounted and a shiftable register carriage, which also supports a part of the transfer mechanism.

5 In the calculating machine selected for purposes of illustration, the body of the calculating machine includes side frame plate 10 (Figs. 1 and 2) from which a plurality of transverse brackets 11, 12, 13 and 14 extend to a similar side plate 10 (not shown) at the opposite or right-hand side of the machine as viewed from the front. The side plates are carried by a suitable base (not shown) in the usual manner. Brackets 11 and 14 support rollers 16 on which register carriage 17 is mounted for endwise shifting movement under control of any suitable means.

Carriage 17 (Fig. 1) has frame 18 in which a numeral wheel shaft 19 for each order of the register is journaled. At its upper end each shaft 20 19 carries numeral wheel 21 having the digits from zero to 9 inscribed thereon in the conventional manner, and at its lower end carries ten tooth numeral wheel gear 22. Intermediate its ends, each shaft 19 carries ten tooth ratchet gear 23 with which spring urged ball 24 cooperates to maintain numeral wheel 21 in adjusted position. Shaft 19 also carries resetting gear 25 for cooperation with suitable resetting means not shown.

30 Numeral wheels 21 (Fig. 1) are rotatable in either direction to register positive and negative values and for this purpose ten-tooth gear 22 has associated therewith a pair of opposed ten-tooth bevel gears 26, 27 (Figs. 1 and 2) formed at the ends of spool 28. The shifted positions of gears 26, 27 are controlled by transversely extending strap 29 positioned between each pair of gears 26, 27 of the various orders of the machine. Strap 29 may be mounted in a convenient manner as by one or more arms 30 for movement forwardly and rearwardly of its central neutral position shown in Fig. 1 to engage gears 26 or 27 with numeral wheel gears 22. Thus, if gears 26 are engaged with gears 22, positive actuation of 45 the associated numeral wheels 21 will occur, and, conversely if gears 22 are engaged with gears 27, negative actuation of numeral wheels 21 is determined.

From the above description, it is seen that any 50 increment of movement of a spool 28 will be transmitted to the associated numeral wheel 21 if either of gears 26 or 27 is placed in active position.

Means are provided in the various orders of 55 the machine to determine the number of incre-

ments of such movement. For this purpose a bank of numeral keys 31 is provided for each order of the machine, only a part of one of such banks being shown in Fig. 1. The numeral keys 31 of each blank of the machine cooperate with a pair of differential value selecting slides 32, 33 which are mounted for endwise shifting movement and are provided with cam surfaces of varying inclination to be set differentially in accordance with the value of the depressed numeral key. At their rearward ends, slides 32, 33 carry respective ten-tooth gears 34, 35 which cooperate respectively with the two sets of stepped teeth 36, 37 on an actuating cylinder 38 of the digitation actuating mechanism.

Gears 34, 35 (Figs. 1 and 3) are mounted for sliding movement on square shaft 39 having its front end journaled in bracket 13 and extending rearwardly through bracket 12 and spool 28, and having its rear end journaled in bracket 11. Teeth 36 cooperate with gear 34 in their relatively adjusted positions to determine movement of shaft 39 for from six to nine increments, while teeth 37 and gear 35 cooperate to determine movement of shaft 39 for from one to five increments. A pair of cylinders 38 are mounted on each actuating shaft 41 for a pair of adjacent orders, the respective actuating shafts 39 of such adjacent orders being spaced to either side and above the associated actuating shaft 41 as clearly seen in Fig. 3. Each actuating shaft 41 is journaled in brackets 13 and 69 and at its front end has a bevel gear connection 42 with transverse shaft 43. Shaft 43 has its ends journaled in respective side plates and is driven cyclically from a suitable source of power such as an electric motor, or a hand crank. In the embodiment shown, one cycle of operation is effected by one rotation of shaft 43. Thus, for each rotation of shaft 43, shafts 41 and cylinders 38 also have a single rotation to cause registration of the number selected by the depressed numeral keys 31 on the associated numeral wheels 21.

Means are provided for preventing overthrow of the numeral wheels at the end of an actuation thereof and for this purpose the two sets of stepped teeth 36, 37 (Fig. 1) of each cylinder 38 are located with their last active teeth in alignment and there is associated with each shaft 39, a Geneva wheel 46 (Figs. 1-3) mounted thereon for rotation therewith, and associated with each Geneva wheel 46 is a locking disc 47 on an actuating shaft 41 and having a recessed portion 48 extending around its periphery for a distance corresponding to the distance occupied by teeth 36 on the associated cylinder 38. Each Geneva wheel 46 (Fig. 3) has ten concave faces for cooperation with the associated disc 47 so that for each increment of movement imparted to shaft 39 and Geneva wheel 46 by one of teeth 36 or 37, one of the faces is positioned for cooperation with associated disc 47. The trailing edge of recessed portion 48 moves into engagement with Geneva wheel 46 immediately after the last active tooth of teeth 36, 37 has actuated one of gears 34 or 35 so that the associated shaft 39 and, consequently, the associated numeral wheel 21, are positively locked against further rotation. To center shaft 39 and Geneva wheel 46 in position after movement thereof, shaft 39 carries ten tooth ratchet gear 49 (Fig. 1) adjacent frame bracket 11 which has spring-pressed ball 50 mounted therein for cooperation with gear 49.

Each pair of locking discs 47 for adjacent or-

ders of the machine are mounted on actuating shaft 41 in axially offset relation, in the same manner and for the same purpose as the similar mounting of the associated actuating cylinders 38.

Cyclically operable transfer mechanism of conventional construction is provided for cooperation with the actuating cylinders described above and generally such transfer mechanism comprises tripping means associated with each numeral wheel, except that of highest order, for enabling a drive connection from a transfer actuator to the numeral wheel of next higher order, so that such next higher order numeral wheel receives one increment of movement when the numeral wheel of lower order passes from 9 to zero or zero to 9. The sign character of the transferred increment is determined in the same manner as the sign character of the digitation increments.

To effect the tripping of a transfer, each numeral wheel shaft 19 (Figs. 1 and 5) is provided with single tooth gear 51 immediately below carriage frame 18 for cooperation with tripping lever 52, pivoted at 53 in frame 18 and yieldably held therein by spring-pressed ball 54 engaging a slightly off-center seat in pivot 53. Lever 52 has extension 55 (Fig. 5) positioned in the path of single tooth gear 51 of one order, so that when the numeral wheel passes from nine to zero or zero to 9, extension 55 is engaged by the tooth of gear 51 and lever 52 is rocked in a clockwise direction as viewed in Fig. 5, the limit of such movement being determined by the engagement of face 55a of extension 55 with the next adjacent tripping lever 52. The clockwise rocking is against the urgency of spring-pressed ball 54 (Fig. 1) which yieldably maintains the lever in the position shown in Figs. 1 and 5.

Lever 52 is also provided with arm 56 extending into the next higher order of the machine and normally engaging lever 52 of such order adjacent to its pivot 53. Arm 56 has bend end 57 (Fig. 1) which extends downwardly and engages rearwardly of annular flange 58 of gear hub 59. Hub 59 carries transfer gear 61 and is slidably mounted on shaft 39 so that rocking movement of tripping lever 52 results in shifting hub 59 and gear 61 forwardly of the machine to position gear 61 in operative relation with respect to the transfer actuator therefor. Single tooth cyclic transfer actuator 62 (Figs. 1-3) for gear 61 is suitably mounted with actuator 62a of the adjacent lower order by suitable studs on the associated locking discs 47. To enable movement of shaft 39 by operation of actuator 62 and to prevent overthrow thereafter, each locking disc 47 is provided with a transfer notch 63 (Fig. 3) spaced from recessed portion 48 by an interposed solid portion 64 of disc 47.

From the above description it is seen that each time a transfer is determined in one order of the machine, gear 61 of the next higher order is moved into active position to be subsequently operated by the associated transfer actuator 62.

Means are provided for resiliently maintaining gear 61 in either shifted position thereof and associated with such maintaining means is a restoring cam, which operates with each pair of adjacent gears 61. Gear hub 59 (Fig. 1) has a second annular flange 66 which extends between spaced annular flanges 67 of shaft 68, which is slidably mounted in transverse member 69 secured on bracket 12 and spaced therefrom, and transverse member 71 spaced from member 69 and suitably supported on the frame of the machine. Shaft 68 is suitably maintained resiliently

in either shifted position thereof. It will be noted that when gear 51 is moved to operative position the forward end of shaft 68 will project beyond member 69 and into the path of restoring cam 72 (Figs. 1 and 2) preferably formed integrally with actuator 62a of each pair of associated transfer actuators. It will be seen that the successive pairs of actuators 62, 62a on the remaining actuating shafts 41 are spaced apart an angular distance to provide for successive operation of the transfer actuators from the lowest to the highest order.

The above described mechanism is all of conventional construction being described and claimed in my co-pending application Serial No. 75,307, filed April 20, 1936. Usually, one or more extra transfer orders of the character described above are provided in orders which do not have any digitation actuation therewith. However, the number of such orders which can be utilized in a 360° cycle is limited, and the present invention is concerned with provision of additional transfer orders which are of a character to extend the transfer capacity of the machine without requiring the same amount of time in the cycle as the cyclically timed transfer mechanism of the type described above.

The non-cyclic transfer mechanism of the instant invention is not definitely timed with the cyclically driven mechanism of the machine, but is dependent for its timing solely upon the step-by-step transfer from numeral wheel to numeral wheel. The transfer is preferably effected directly by the numeral wheel of next lower order in passing from zero to 9 or 9 to zero, as the case may be.

The non-cyclic transfer mechanism includes bracket 75 (Figs. 2, 3 and 4) which is mounted in a horizontal position to extend through cut-away portion 76 of left side plate 10. Bracket 75 is provided with upright ears 77, which may be suitably secured to the plate 10 as at 78. Two similar transfer units are mounted on the bracket 75 and as the units are identical in construction only one will be described in detail.

Each transfer unit includes a substantially T-shaped setting lever 81 which is pivoted by stud 82 on L-shaped actuating bellcrank 83 pivoted by stud 84 on bracket 75. The T-shaped setting lever 81 is therefore capable of a compound movement, one given by its own pivotal mounting at 82 and the other given by the pivoting of bellcrank 83 at 84. These two movements are utilized in conditioning and selecting the direction of the transferred increment, and in actually performing the transferring operation.

Setting lever 81 (Figs. 2 and 4) is provided with opposite upturned ears 86 on which respective spring urged actuating pawls 87 are pivoted at 88. Each pawl 87 is provided with an actuating tooth 89 and an offset ear 91 which is below the pivotal axis and is connected by a spring 92 with an extension of ear 86. The spring 92 urges the pawl 87 in a counterclockwise direction as viewed in Fig. 3 so that the offset ear 91 is normally held in engagement with the side of upturned ear 86 to provide a stop for the pawl. In this position the nose 89 is in the plane of the numeral wheel gear 22 as shown in Fig. 4 but is normally disposed out of the path of the numeral wheel gear so that the carriage can be shifted freely.

As seen most clearly in Figs. 2 and 4, the respective pawls 87 at the opposite sides of a numeral wheel gear 22 can be moved into en-

gagement therewith by oscillation of the transfer lever 81 about its pivot 82 and preferably this movement is controlled by the strap 29 which shifts the plus-minus gears of the machine so that the transfer unit is similarly conditioned for either positive or negative operation.

To effect this conditioning movement, setting lever 81 (Figs. 2 to 4) is provided with a bifurcated extension 96 which embraces a stud 87 upstanding from the strap 29. Thus movement of the strap 29 in either direction from a central neutral position as shown in Fig. 4 will cause oscillation of the lever 81 about its pivot 82 to move one of the pawls 87 into engagement with the aligned numeral wheel gear 22. This condition of the parts is shown in Fig. 6.

To effect the operating portion of the transferring operation, actuating lever 83 is adapted to be operated by the transfer lever of the numeral wheel of next lower order. The movement of the lever 83 (Fig. 2) about its pivot 84 is controlled by the engagement of respective stop surfaces 101 and 102 thereof with pin 103 on bracket 75. As shown in Fig. 2 in the neutral position of the lever 83, spring 104 maintains stop surface 101 in engagement with pin 103.

To provide for operation thereof, actuating lever 83 is provided with upstanding ear 106 (Figs. 2 and 4) which is adapted for engagement with depending ear 57 of the transfer lever 52 of next lower order. Thus, when the next lower order transfer lever 52 is oscillated by its associated transfer gear 51, lever 83 will be rocked from the position shown in Fig. 6 to that shown in Fig. 7. During this movement the tooth 89 engaged with the numeral wheel gear 22 will advance such gear for one tooth space. When the lever 83 rocks back the pawl 87 yields and its nose 89 snaps under the tooth of gear 22 which is maintained in its adjusted position by the overthrow preventing and centralizing means 23 and 24 (Fig. 1).

The operation of the transfer mechanism is as follows: When a registration is started and the strap 29 is moved rearwardly of the machine to determine a positive registration for example, that is, to the position shown in Fig. 6, the pins 87 carried by the strap 29 oscillate the levers 81 in a counterclockwise direction to the position shown in Fig. 6, where the noses 89 of the respective pawls 87 are moved into engagement with a tooth of the aligned numeral wheel gear 22. If during the registration a transfer is determined from the numeral wheel of next lower order, its one tooth gear 51 oscillates the aligned transfer lever 52 so that its depending ear 57 oscillates the associated lever 83 in a clockwise direction so that lever 81 is moved to the right as viewed in Fig. 2 from the position shown in Fig. 6 to that shown in Fig. 7. This is sufficient to effect a one-step movement of the numeral wheel gear 22 with which it is engaged so that the transferred increment is entered therein.

While I have shown and described a preferred embodiment of the invention, it will be understood that the invention is capable of both variation and modification from the form shown, so that its scope should be limited solely by the scope of the claims appended hereto.

I claim:

1. In a calculating machine, a shifttable carriage, numeral wheels on said carriage, each numeral wheel having a numeral wheel gear associated therewith, transfer levers on said carriage and cooperatively related with said numeral

wheels for movement in response to passing of the associated numeral wheel from 9 to zero or zero to 9, a transfer actuating lever mounted for movement in the machine in a direction substantially parallel to the direction of shifting movement of said numeral wheel gears, a transfer setting lever pivotally mounted on said transfer actuating lever for movement in a direction substantially transversely to the direction of movement of said numeral wheel gears, a pair of pawls carried by said transfer setting lever and positioned at opposite sides of a numeral wheel gear aligned therewith, and means for selectively engaging said pawls with the said aligned numeral wheel gear, said transfer actuating lever being operable by the aligned one of said transfer levers upon movement of the associated lower order numeral wheel from 9 to zero or zero to 9 to effect a transferring operation by movement of the pawl engaged with the said aligned numeral wheel.

2. In a calculating machine, shiftable numeral wheels including a numeral wheel gear associated with each numeral wheel, said gears being movable through a path in ordinal step-by-step fashion, plus-minus gears associated with said numeral wheel gears for selectively effecting movement thereof in opposite directions, means for moving said plus-minus gears selectively into cooperative relation with said numeral wheel gears, a transfer lever, means for moving said lever in a direction substantially transversely to the direction of movement of said numeral gears along said path, a pair of transfer pawls carried by said lever and selectively movable into engagement with a numeral wheel gear aligned therewith, and means for moving said lever in a direction of movement of said numeral wheel gears along said path to effect a one step movement of said aligned numeral wheel gear.

3. In a calculating machine having a frame, a carriage mounted for endwise shifting movement on said frame to various ordinal positions, a series of ordinarily arranged numeral wheels on said carriage, a series of pivotally mounted levers on said carriage, each lever being associated with one of said numeral wheels for movement in response to movement of the said associated numeral wheel from "0" to "9" or "9" to "0", and cyclically operable transfer actuating mechanism in said frame for operation under control of said levers and disposed to effect transferring operations with the numeral wheels of lower orders; non-cyclic transfer means for continuing transferring operations for at least one order higher than the capacity of said cyclically operable transfer mechanism, said transfer means also operating under control of said numeral wheels by means of said levers.

4. In a calculating machine, a shiftable carriage, numeral wheels on said carriage, numeral wheel gears associated with said respective numeral wheels to transmit increments of movement thereto, transfer levers on said carriage and cooperatively related with said numeral wheels for movement thereby, each of said transfer levers being operated in response to movement of the associated numeral wheel upon passing from "9" to "0" or "0" to "9", a transfer actuating lever mounted in the machine for movement in a direction substantially parallel to the direction of shifting movement of said numeral wheel gears, a transfer setting lever mounted on said transfer actuating lever for movement in a direction substantially transversely to the direction of movement of said nu-

meral wheel gears, a pair of pawls carried by said transfer setting lever and positioned at opposite sides of the numeral wheel gear aligned therewith, means for operating said transfer setting lever upon selection of the direction of actuation of said numeral wheels to engage one of said pawls with the aligned numeral wheel gear, and means responsive to the operation of a transfer lever of the order next lower than the order associated with said pawls for operating said transfer actuating lever and for effecting a transferring operation on a numeral wheel by the active pawl engaged with the associated numeral wheel gear.

5. In a calculating machine, a shiftable carriage, numeral wheels on said carriage, numeral wheel gears associated with said respective numeral wheels to transmit increments of movement thereto, a transfer actuating lever pivotally mounted in the machine and extending in a direction substantially transverse to the direction of shifting movement of said numeral wheel gears, a transfer setting lever pivotally mounted on said transfer actuating lever and extending in a direction substantially parallel to the direction of movement of said numeral wheel gears, a pair of one-way acting pawls carried by said transfer setting lever and positioned at opposite sides of the numeral wheel gear aligned therewith, means for operating said transfer setting lever upon selection of the direction of actuation of said numeral wheels to engage one of said pawls with the aligned numeral wheel gear, and means responsive to the passing of a numeral wheel from "9" to "0" or "0" to "9" in the order next lower than the order associated with said pawls for operating said transfer actuating lever and for effecting a transferring operation on a numeral wheel by the active pawl engaged with the associated numeral wheel gear.

6. In a calculating machine of the type having cyclically operable actuating means and a carriage mounted for endwise shifting movement relative to said actuating means, said carriage having a series of numeral wheels mounted therein, transfer mechanism driven cyclically with said actuating means for performing transferring operations on aligned numeral wheels, a series of movably mounted transfer levers on said carriage, each lever being movable in response to movement of the associated numeral wheel from 9 to zero or zero to 9, transfer means cooperatively related to at least one numeral wheel of higher order than those associated with said transfer mechanism, said transfer means including an element for actuating the aligned one of said numeral wheels and means for operating said element by the said transfer lever associated with the numeral wheel of next lower order upon operative movement of said lever.

7. In a calculating machine having actuating means, a shiftable carriage movable relative to said actuating means and numeral wheels in said carriage, each numeral wheel having a drive receiving element, transfer means for at least one of said numeral wheels, said transfer means including a part having a movement from a normal inoperative position into operative engagement with the aligned numeral wheel element and another movement for transmitting a transferred increment to said numeral wheel element, means for engaging said transfer mechanism with an aligned numeral wheel element upon conditioning the machine for a registering operation by said actuating means, and means for causing

a transferring operation of said transfer means upon movement of the numeral wheel of next lower order from zero to 9 or 9 to zero, said numeral wheel elements being freely shiftable past said transfer means in the normal inoperative position of said part.

8. In a calculating machine having an endwise shiftable carriage and a series of numeral wheels in said carriage having drive receiving elements whereby said numeral wheels and said elements are movable through a path upon shifting of the

carriage, positive and negative transfer elements at either side of said path, means for selectively moving one or the other of said transfer elements into operative engagement with the drive receiving element aligned therewith, and means for effecting a transferring movement of the operative transfer element in response to movement of the next lower order numeral wheel from zero to 9 or 9 to zero.

CARL M. FRIDEN.
